SHEET FEEDING AND DELIVERING
MECHANISM

Robert Stuart, Forest Hills, N. Y.

Original application May 27, 1933, Serial No. 673,203. Divided and this application August 6, 1934, Serial No. 738,609

10 Claims. (Cl. 197—130)

This invention relates to sheet feeding and delivering mechanism for typewriters, and is herein shown embodied in, although not restricted for use with, the machine shown, described and claimed in my pending application Serial No. 673,203, filed May 27, 1933, of which the present application is a division. The machine to which said application Serial No. 673,203 is directed includes a projecting apparatus by which minute records, such as informative data respecting each of a multitude of addresses, may be enlarged and projected on a screen so as to enable the typist to utilize the projected subject matter as a guide or copy, the projecting apparatus being separately claimed in my pending application Serial No. 738,610 of even date, also a division of said application Serial No. 673,203.

An object of the invention is to provide an improved sheet feeding and delivering mechanism by which sheets of paper may be automatically delivered to and placed one after another in proper writing position on the platen roll of a typewriter, and by which such sheets may be automatically ejected or discharged from the platen roll and successively stored, thus relieving the typist of all labor in such positioning, ejecting and storing.

Other objects and advantages of the invention will become apparent from the following description, taken in connection with the accompanying drawings, in which—

Fig. 1 is a profile view of the complete apparatus, some of the parts being omitted and others shown in section for purpose of clarity; Fig. 2 is a profile view of a portion of the apparatus, particularly illustrating the shape of one of the side frame plates and the belt drive connections to the conveyer rollers; Fig. 3 is a front view of the apparatus, some of the parts being omitted for purpose of clarity; Fig. 4 is an enlarged plan view, partly in section, of the typewriter platen roll and parts associated therewith; Fig. 5 is a cross-sectional view of parts, taken on the plane indicated by the arrows 5×—5× in Fig. 4; Fig. 6 is a detail view taken on the plane indicated by the arrows 6×—6× in Fig. 5 particularly illustrating the construction of the cooperating cams determining the extent of rotation of the platen roll; Fig. 7 is a cross sectional view of parts, taken on the plane indicated by the arrows 7×—7× in Fig. 4; Fig. 8 is a detail view taken on the plane indicated by the arrows 8×—8× in Fig. 4, particularly illustrating the tripping mechanism for starting the apparatus; Fig. 9 is a view of parts, taken on the plane indicated by the arrows 9×—9×

in Fig. 4; Fig. 10 is a view taken on the plane indicated by the arrows 10×—10× in Fig. 4, particularly illustrating parts immediately in the rear of the platen roll and movable therewith; Fig. 10A is a detail view taken on the plane indicated by the arrows 10A×—10A× in Fig. 12, particularly illustrating one of the rear fingers movable with the platen roll; Fig. 11 is a detail view taken on the plane indicated by the arrows 11×—11× in Fig. 4, particularly illustrating the cooperating cam-grooved wheel and roller-carrying slotted lever, which serve to actuate the suction sheet feeding devices; Fig. 12 is a view taken on the plane indicated by the arrows 12×—12× in Fig. 10, particularly illustrating the rear roller and fingers 15 movable with the platen roll; Fig. 13 is an enlarged profile cross-sectional view of the upper front portion of the projector, particularly illustrating shutter mechanism parts; Fig. 14 is a rear view taken on the plane indicated by the arrows 14×—14× in Fig. 13, particularly illustrating other parts of the shutter mechanism; Fig. 15 is a detail view taken on the plane indicated by the arrows 15×—15× in Fig. 1, particularly illustrating rocking parts for actuating the shutter 25 mechanism; Fig. 16 is an enlarged view of a portion of the apparatus, taken on the plane indicated by the arrows 16×—16× in Fig. 1; Fig. 17 is an enlarged profile view of the film reeling mechanism and other parts associated therewith; 30 Fig. 18 is a plan view of parts, taken on the plane indicated by the arrows 18×—18× in Fig. 17; Fig. 19 is a cross-sectional detail view taken on the plane indicated by the arrows 19×—19× in Fig. 17, particularly illustrating one of the reels and supporting mechanism therefor; Fig. 20 is a cross-sectional view of details, taken on the plane indicated by the arrows 20×—20× in Fig. 17; Fig. 21 is a detail view of the film actuating mechanism 35 clutch control, taken on the plane indicated by the arrows 21×—21× in Fig. 18; Fig. 22 is a detail view taken on the plane indicated by the arrows 22×—22× in Fig. 4, particularly illustrating the cooperating cam-grooved wheel and roller-carrying slotted lever, which serve to actuate the mechanism 40 for moving the sheet supply and storage magazines; Fig. 23 is a detail view taken on the plane indicated by the arrows 23×—23× in Fig. 1, particularly illustrating parts of the mechanism for moving said magazines; and Fig. 24 is an enlarged view of parts of said mechanism.

Referring to Figs. 1, 2 and 3, a typewriter 1 is shown positioned on a fixed base or desk top 2 to permit manipulation of its keyboard and is preferably fixedly secured in this position to 55

said base 2. This typewriter, insofar as its manual operation is concerned, is of standard construction, no detailed description of its usual parts being required, but, to adapt it to have 5 sheets automatically fed to its platen roll 4 and placed in writing position thereon, its usual sheet supporting or guiding plate 5 is formed with a longitudinal slot 6', as best illustrated in Figs. 10 and 12, and carries at its rear further parts 10 for movement therewith. These additional parts and the particular purpose of the slot 6' will be described hereinafter. Of course, the plate 5, as in the usual construction, is in fixed relation with the typewriter carriage and therefore moves 15 laterally in either direction with the platen roll 4.

Overhanging the typewriter 1 are a sheet feeding conveyer 6 and a sheet discharging conveyer 7, each comprising spaced guide plates suitably supported by side plates 8 and 8a fixedly extending from the base 2, one of the plates, 8a, being shaped as shown in Fig. 2 to allow proper lateral movement, in either direction, of the typewriter carriage and a sheet therein. As shown by an inspection of Fig. 3, these conveyers are disposed 20 at one side to cooperate with the typewriter carriage when the latter is in its extreme left position, determined by one of the usual adjustable stops (not shown). The lower portion of the feed conveyer 6 slopes to the same extent as the typewriter guide plate 5, and, for said position of the typewriter carriage, the lower edge or discharge end of said conveyer 6 is slightly spaced from the upper edge of said plate 5 and the latter is in direct alignment with the lower guide plate of 25 said conveyer 6 so as to form a virtual continuation thereof. The discharge conveyer 7 is positioned above the feed conveyer, a laterally extending hinge 9 being provided to permit its lower portion 7a to be swung from its position shown in Fig. 1 to its position shown in Fig. 2, so as not to hinder the operator's movements when it is desired to remove sheets from the typewriter by hand or both insert and remove sheets into and from the typewriter by hand. 30 The pivotal portion 7a may be detachably held in its upper position by any suitable means. When in its lower position, the lower edge or intake end of the conveyer 7 is so positioned relatively to the typewriter that the sheets, as they are ejected, when typed upon, by successive rotations or line-spacing actuations of the platen roll 4, or, when the carriage is in its extreme left position, by automatic rotation of the platen roll 4 as will be hereinafter described, enter said 35 conveyer 7 between its guide plates.

Blank sheets 10, or the sheets to be addressed in the typewriter, are fed into the conveyer 6 from a vertically movable container or magazine 11, which is provided with an open side contiguous to the intake end of said conveyer 6. The typewritten sheets are discharged from the conveyer 7 into another vertically movable container or magazine 12, which is provided with an open side contiguous to the discharge end of said conveyer 7 and which stacks the sheets it receives. As will be hereinafter more clearly understood, the apparatus operates to remove the sheets from the magazine 11, only one at a time and only one during each operation of 40 the apparatus (for conveyance to and proper positioning on the platen roll 4), and to advance or store the sheets into the magazine 12, only one at a time and only one during each operation of the apparatus (after its ejection and conveyance from the platen roll 4). Thus, in order 45

that the upper exposed sheet of the stack in the magazine 11 be maintained at the proper level relatively to the intake end of the conveyer 6, the sheet supply magazine 11 is displaced upwardly a given distance, whenever the stack 10 5 has been depleted to an extent making this operation necessary. Simultaneously therewith, the sheet storage magazine 12 is displaced downwardly the same distance. The mechanism causing these simultaneous displacements of the two 10 magazines will be described hereinafter. Each of the magazines is equipped with the usual adjustable means (not shown) for properly positioning and stacking the sheets in accordance 15 with their size.

Each of the conveyers 6 and 7 also comprises a plurality of belt-driven rollers 14 and a corresponding number of spring-pressed idlers 15 cooperating therewith. All of these rollers are rotatably mounted on the frame or side plates 8 20 and 8a, operate through laterally extending slots formed in the guide plates of said conveyers, and are adapted to be rotated continuously as will be seen, the cooperating roller pairs of each conveyer acting in turn to engage opposite surfaces of a guided sheet to advance or convey it in the proper direction, as determined by their rotation.

These rollers are of such length and the cooperating pairs of each conveyer are disposed at such intervals that sheets of varying size may be properly conveyed in the manner described. Thus, the sheet-supply stack 10 may vary in regard to the size of the sheets it contains, a pair of section sheet feeding devices 16 (only one being shown) to be hereinafter more particularly described, acting to transfer said sheets from the magazine 11 seriatim to the first cooperating roller pair 17 of the conveyer 6 at its intake end, being thereafter discharged by the last cooperating roller pair 19 into the lower sloping portion of said conveyer 6, through which they travel by reason of weight and velocity and from which they are wholly or partly discharged on the guide plate 5 of the typewriter carriage (in its extreme left position). With the first cooperating roller pair 20 of the conveyer 7 properly disposed relatively to the platen roll 4 (in its extreme left position), each of the sheets (assumed to have been properly positioned on the platen roll 4 for the present) as it travels between the guide plates of said conveyer 7 (by automatic rotation of the platen roll 4, as will be understood), may be gripped by said pair 20 to be discharged by the last cooperating roller pair 21 of said conveyer 7 into the storage magazine 12.

The power for actuating the apparatus is furnished by a motor 22 suitably secured to the base 2. As shown in Fig. 16, the motor shaft drives 60 a pair of cooperating bevel gears 24 and 25, one of these, 25, being secured to the lower end of a vertical shaft 26 extending through the base 2. Said shaft 26 is rotatably mounted at its lower end in a bearing 27 forming part of a support 29 65 fixed to the base 2 and above the base 2 in a bearing 30 secured to the side plate 8. Said shaft 26 is prevented from moving axially and may be mechanically connected at its upper end by a clutching device 34 to a bevel gear 35 rotatably mounted in a horizontal frame piece 36 secured at its ends to the side plates 8 and 8a. A shaft 31 is rotatably mounted in a bearing 39 fixed to the plate 36 and in the side frame plate 8a and carries at its inner end a bevel gear 40 meshing 70

with the aforesaid gear 35. At its outer end said shaft 37 carries a double pulley 41.

Referring to Fig. 2, said pulley 41 cooperates with a belt 42 which drives a double pulley 43 fixed to the shaft of the roller 14 of the cooperating pair 20. The remaining rollers 14 of the conveyer 1 are each provided with a pulley 44 driven by another belt 45 cooperating with said double pulley 43. An idler or tightening roller 46 is provided to keep the belt 45 in contact with all of its cooperating pulleys and is rotatably mounted in the side plates 8 and 8a. The roller 14 of the cooperating pair 19 is also provided with a double pulley 47, which is rotated by the aforesaid double pulley 41 through the intermediary of a full-twist or cross-belt 49 producing a reverse motion of the driven roller. The roller 14 of the other cooperating pair 17 is driven by another belt 50 cooperating with said pulley 47. With the motor 22 running and the shaft 26 and gear 35 connected by the clutching device 34, the various rollers of the two conveyers 6 and 7 are thus caused to rotate continuously.

The clutching device 34 comprises a toothed tubular element 51 fixed to the gear 35 and a cooperating toothed tubular element 52 slidably keyed to the shaft 26 so as to rotate therewith. As shown in Fig. 9, the shaft 26 is rotatable within said gear 35 and element 51, which are rotatable as a unit. A spring 54 disposed between the element 52 and a fixed collar 55, holds the toothed elements 51 and 52 in mesh. A bell-crank control 56 is pivotally carried by a bracket fixed to the frame piece 36 and has a pin which rides in a circular groove 58 on the slidable element 52 and a detent 59 to cooperate with an opening 60 in the frame piece 36. Said control, when operated to cause the detent to drop into the opening, disengages the clutch elements 51 and 52 against the spring 54. This clutching device 34 permits stopping the rotation of the conveyer rollers, when it is desired to insert and remove sheets on and from the platen roll 4 by hand. Its control 56 may be manipulated through an opening 61 in the side frame plate 8.

A worm 62 is fixed to the actuating shaft 26 and, as shown in Fig. 4, meshes with a worm-wheel 64, which therefore rotates continuously. Referring to Fig. 7, said wheel 64 is loosely engaged by a shaft 66 so as to be rotatable thereon. Said shaft 66 is rotatably mounted in the side frame plate 8 and in a bearing 65 secured to the frame piece 36, a fixed collar 69 preventing outward movement thereof. The wheel 64 is provided with a hollow toothed hub or clutching member 71, within which a collar 68, fixed to the shaft 66, is disposed. The collar 68 and the bearing 65 prevent axial displacement of the wheel 64, inward movement of the shaft 66 being also prevented. Slidably keyed to the same shaft is a gear 72, also comprising a toothed hub portion 74 extending toward said element 71. Said gear 72 is rotatable on a ball-thrust bearing 75, the spring 76 of which provides pressure on the gear for moving it and the clutching member 71 inwardly and holding the latter locked to the clutching member 71. These members 71 and 74, however, are normally restrained from meshing by a bar or cam 77 on which normally rests a lug 79 fixedly extending from said gear 72. Said element 77 will be hereinafter more particularly described.

In the embodiment of the invention illustrated, a foot-pedal 80 is provided to start the operation of the apparatus. Referring to Fig. 1, this

pedal 80 is suitably pivoted below the table top 2 and its rearward extension 80a is loosely pivotally connected to a short link 81, itself suitably pivoted below the top 2 and pivotally connected at its rear to a rod 82, extending through the top 2 and, as shown in Fig. 7, slidably held at its upper end by the frame piece 36. Upon depressing the pedal 80, the rod 82 is caused to move downwardly. Upon releasing the pedal, a spring 83, acting on a fixed collar 78, raises both the rod 82 and the pedal to their normally inoperative positions. Referring to Figs. 7 and 8, the rod 82 has pivotally connected thereto a finger or trip 84 which is provided at its free end with a laterally extending lug 85 normally held against an edge 15 of the rod by a spring 83, fixed at its ends to the rod and to the trip. Said lug 85 is normally disposed above and is adapted to cooperate with a pin 86 fixed to a latch 87 held at its edges by guiding elements 89 secured to a vertical bracket 90 supported by the frame piece 36. Said latch 87 enters a notch formed on the aforesaid bar 77 and is normally held therein by a spring 91, fixed at its ends to the bracket and to the latch. The bar 77 is slidable in the bracket 90 and is provided with a pin 92 extending through a slot 94 (Fig. 4) into a recess or chamber 95 in said bracket 90. A spring 96 is mounted in said chamber 95 and provides lateral pressure on the pin 92 for the purpose of restoring the bar 77 to its normal position of rest.

When depressing the pedal 80, the lug 85 causes the pin 86 to move outwardly thereon, thus unlatching the bar 77 which therefore permits the spring 76 to move the gear 72 and member 74 inwardly against the weaker spring 96 and thus lock the members 71 and 74 together. Rotation is immediately applied to the gear 72 and shaft 66, the lug 79 riding off the bar 77 which is brought back to its normal position of rest by the spring 96. The lug 85, in its downward movement, completely clears the pin 86, thereby permitting the spring 91 to move the latch 87 back into locking engagement with the bar 77. Upon releasing the pedal 80, the lug 85 in its upward movement is forced outwardly by the pin 86 which rides inwardly thereon, finally clearing the pin, whereupon it is again brought into engagement with the edge of the rod 82 by the spring 83. However, should the pedal 80 be released before the lug 79 has left the bar 77, i. e., prior to the resetting movements of the bar 77 and latch 87, the lug 85 travels in its upward movement in engagement with the rod 82 between the latter and the pin 86, finally clearing said pin which is then free to move under the action of the spring 91 to its normal position of rest. It is to be particularly noted that the gear 72 and shaft 66 are stopped rotating after having completed a full revolution, because of the declutching action, on the members 71 and 72, of the cooperative cam surfaces formed on the members 77 and 79. Thus, each time the operator depresses the pedal 80, the gear 72 and shaft 66 are caused to rotate one complete revolution.

In mesh with the gear 72 is another gear 97 bearing a one to one ratio therewith and fixed to a shaft 99. The latter, as more clearly illustrated in Fig. 5, is rotatably carried at one end by a bearing or support 100 secured to the frame piece 36 and at its other end by the side plate 8. Axial displacement of the shaft 99 is prevented by the gear 97 and by an outer crank member 101, also fixed thereto. The function of the member 101 will be described hereinafter.

A toothed collar or clutching member 105 is slidably keyed to the shaft 99 and, under the influence of a spring 106, normally meshes with the toothed portion 107 of a gear 109. The latter is loosely mounted on the same shaft and lateral displacement thereof is prevented by an inner fixed collar 103. This collar 105 has a pin 110 fixed thereto and extends through a pair of apertured cam members 111 and 112, which cooperate with said pin 110 in a manner which will be hereinafter more clearly understood. One of these members, 111, is fixed to the frame piece 36 and the other, 112, is loosely or rotatably held in the fixed member by an apertured bracket 114 secured to said frame piece 36. A handle 115, extending from the movable member through a slot in the frame piece 36, is provided with a spring-pressed pin 116 slidably cooperating with a curved rack 117 (as best illustrated in Fig. 9), this construction permitting adjusting the position of said movable member relatively to the fixed member. As shown in Fig. 3, the handle 115 may be manipulated from the front of the apparatus. As best illustrated in Fig. 6, the fixed member 111 is formed with a circular track 119 having an arcuate tooth or raised cammed portion 120 and the adjustable member 112 is similarly formed with a circular track 121 also having an arcuate tooth or raised cammed portion 122. Said raised portions 120 and 122 overlap one another for any position of the handle 115.

It being observed that the collar 105 rotates one complete revolution only, each time the pedal 80 is depressed, the position of the pin 110 is by necessity the same at the start and at the end of such rotation. This normally inoperative position of the pin 110 is shown in the drawings, namely on the low portions of both tracks 119 and 121 and adjacent to the raised portion 120 of the fixed member 111. Upon depressing the pedal 80, the pin 110 is carried in the direction of the arrow in Fig. 6, riding on both of said low track portions until it reaches and is raised by the cammed portion 122 of the adjustable member 112, this causing the member 105 to become separated from the member 107 against the force of the spring 106. The gear 109 stops rotating, but the pin 110 continues rotating with the collar 105, first riding on said raised portion 122 alone, then on both raised portions 122 and 120, and then only on the raised portion 120 of the fixed member 111. It finally slides off the latter cammed portion 120, its rotation being arrested at the instant it assumes its original position shown in the drawings, with the clutching members 105 and 107 in mesh. It now becomes apparent that the rotation of the gear 109 may be controlled, i. e., its extent of rotation varied, by adjusting the position of the handle 115.

Referring particularly to Fig. 4, the gear 109 meshes with a smaller gear 124 fixed to a shaft 125 rotatably mounted, in axial alinement with the platen roll 4, in a bearing or support 126 fixed to the side plate 8. Said gear 124 and a fixed collar 127 prevent lateral displacements of the shaft 125. Said gear 124 is provided, at its side facing the platen roll 4, with a toothed hub portion or clutching member 129, and the usual shaft fixed to the platen roll 4 is provided at its left with the usual knurled wheel 130, but in addition fixedly carries a clutching member 131, which meshes with the member 129 when the typewriter carriage is in its extreme left position.

Assuming, for the purpose of the present de-

scription, the typing of a sheet in the typewriter to have been completed, the operator depresses the usual mechanism (not shown) for releasing the carriage so that it will move to the left, the usual stop (not shown) being so adjusted that the carriage is caused to move the entire extent of its possible travel. (In the usual typewriter construction, the carriage releasing mechanism may comprise a latch or key on the carriage, but, with proper adjustments, a key on the keyboard or either one of a plurality of keys on the keyboard may be caused to effect motion of the carriage to its extreme left position.) With the members 129 and 131 in mesh, the operator depresses the pedal 80, which causes the platen roll 4 to rotate to the extent determined by the position of the control 115 and such sheet to be progressively ejected as a result of this rotation, being caught, prior to interruption of rotation, by the first co-operating roller pair 20 of the conveyer 7 to be transferred by the latter into the sheet storage magazine 12.

Slidably keyed to the inner end of the shaft 66 is a clutching member 132, and in alinement with said shaft 66 is another shaft 67 rotatably carried by a bearing 68 secured to the frame piece 36 and by the opposite side frame plate 8a. A wheel 136 and a clutching member 134 fixed to the shaft 67 on opposite sides of the bearing 68 prevent axial displacement of said shaft 67. Said wheel 136 will be hereinafter more particularly described. During the operation of the apparatus, when it is used to automatically feed sheets to and position them on the platen roll, said members 132 and 134 are kept in constant mesh by a control 171, also to be hereinafter more particularly described. Obviously, with the members 132 and 134 in mesh, each time the pedal 80 is depressed, the shaft 67 is caused to rotate, as the shaft 66, one full revolution, its rotation thereafter being also immediately arrested.

Referring to Figs. 4 and 11, a wheel 137 fixed to the shaft 67 is formed with a cam-groove 138, and a lever 139, having a slotted head 140 mounted on the shaft 67 so as to be guided thereby, carries a roller 141 cooperating with said groove 138. A collar 142 is fixedly secured to the shaft 67 adjacent the outer face of the lever head 140, to keep the roller in the groove. The lever 139 at its other end (see Fig. 1) is pivotally connected to a pivotal arm 144 fixedly extending from a shaft 145 suitably mounted in the side plates 8 and 8a, said arm 144 forming a bell-crank construction through the shaft 145 with the aforesaid pair of suction sheet gripping and feeding devices 16 (only one being shown), also fixedly extending from said shaft 145. The devices 16 are normally positioned with their sheet gripping shoes 16a in engagement or substantial engagement with the top sheet of the stack, the cooperating groove 138 and roller 141 obviously creating reciprocating motion of the lever 139 and thus rocking motion of said shoes. They are of standard construction, the suction necessary for their operation being created through a suitable conduit 146 and in the usual manner being intermittently applied to their shoes. The usual means is provided for directing air currents upon the upper sheets of the stack 10 at their edges to cause the top sheet to become separated, thus permitting the devices 16 to grip and transfer to the conveyer 7 only a single sheet at a time, each time they are made to operate. This means is schematically illustrated by the air nozzle and conduit 147.

It being observed that, with the members 132 and 134 in mesh, the cam-grooved wheel 137 makes one complete revolution each time the pedal 80 is depressed, the position of the roller 141 relatively to the groove 138 must be the same at the start and at the end of such rotation. Now the groove 138 is so designed that, during such rotation, the lever 139 is carried only once in one direction, causing the shoes 16a to be swung toward the first cooperating roller pair 17 of the conveyer 6, and immediately thereafter only once in the opposite direction, causing the shoes 16a to be brought back to their inoperative positions on the remaining stack of sheets. Thus, each time the pedal 80 is depressed, a single sheet is transferred by the shoes 16a from the magazine 11 to the conveyer 6 to be conveyed thereby to the platen roll 4, which as previously stated must then be in its extreme left position. This single cycle of motion of the rod 139 occurs at a predetermined time during the operation of the apparatus, as will be hereinafter more particularly described.

Referring to Figs. 4 and 10, another cam-grooved wheel 149 is slidably keyed to the shaft 67 and its groove 150 cooperates with a roller 154 carried by a second slotted lever 151 mounted on the shaft 67 so as to be guided thereby. Both the wheel 149 and lever 151 are caused to move with the typewriter carriage by a pair of apertured brackets 155 slidably mounted on the shaft 67 and fixedly secured to the rear surface of the typewriter guide plate 5. A washer or spacer 156, positioned between the lever 151 and one of the brackets 155, keeps the roller 154 in the groove 150. Referring to Figs. 10 and 12, the lever 151 at its other end is pivotally connected to a pivotal arm 157 fixedly extending from a shaft 159 pivotally mounted at its ends into brackets 160 fixed to the plate 5. Also fixedly extending from the shaft 159 and forming a bell-crank construction with said arm 157 are a pair of arms 161 carrying a spring-pressed roller 162, which normally cooperates with the platen roll 4 through the aforementioned slot 6'. Another arm 164 is pivotally attached to the lever 151 and is fixed at its other end to another shaft 165 pivotally mounted into brackets 166 fixed to the plate 5. Fixed to the shaft 165 are a pair of arms 167 each of which carries at its end a spring-pressed finger 169. The two fingers 169 are also operative through the slot 6', but are normally spaced from the platen roll 4.

The function of the fingers 169, as will be hereinafter more clearly understood, is to stop a sheet in its descent from the conveyer 6 down the guide-plate 5. I deem this feature of my invention to be an important improvement in the art of automatically feeding sheets to a typewriter and placing them in writing position on its platen roll, inasmuch as it not only properly alines the edges of the sheets relatively to the axis of the platen roll, but also assures their location, at any instant during their subsequent travel in engagement with the automatically rotated platen roll, to be definitely correlated to the various elements necessary to position them automatically on the platen roll, so that each sheet in turn may be caused to occupy the same position at the end of its automatically produced motion on the platen roll. That in turn permits any size sheet to be advanced to writing position on the platen roll, by suitably adjusting the extent of rotation of the platen roll.

With the members 132 and 134 in mesh, the

wheel 149 makes one complete revolution each time the apparatus is operated by the pedal 80 so that the position of the roller 154 in the groove 150 is the same at the start and at the end of such rotation. Now the groove 150 is so designed that, during such rotation, the lever 151 is carried only once in one direction, causing the fingers 169 to engage the platen roll 4 and the roller 162 to become separated from the platen roll 4, and thereafter only once in the opposite direction, causing the fingers 169 and the roller 162 to be restored to their normal positions shown. Each of these two movements of the lever 151 takes place at a predetermined time during the operation of the apparatus, as will be hereinafter more particularly described.

Referring to Figs. 4 and 22, still another cam-grooved wheel 182 is provided on the shaft 67 to which it is secured. The roller 184 cooperating with its groove 183 is carried by a third slotted lever 185 mounted on the shaft 67 so as to be guided thereby. A fixed collar 186 keeps the roller 184 in the groove 183. As illustrated in Figs. 1 and 23, the lever 185 at its other end is connected to one arm of a bell-crank 187 pivotally carried by a vertical frame plate 188 extending from the base 2. The other end of the bell-crank 187 is connected to the lower end of a vertical rod 189. As illustrated in Figs. 23 and 24, the upper end of the rod 189 is provided with a slot 190 in which engages a pin carried by an outer arm 191 forming part of a rocking member 192 loosely mounted on a shaft 193, the latter, as shown in Fig. 1, being rotatably mounted in bearings at the upper edge of the frame plate 188. The rocking member 192 is provided with an inner arm 194 which is weighted and normally held in an uppermost position by a vertical latch 195 fixed to a shaft 193 pivotally carried in standards 197 secured to the plate 188. The rocking member 192 comprises still another arm 198 which has pivotally mounted thereon a pawl 199 cooperating with a ratchet wheel 200 fixed to the shaft 193. As shown in full lines in Fig. 24, the normal position of the member 192, i. e., its position when held against gravity by the latch 195, causes the pin carried by the outer arm 191 to be located at the bottom of the slot 190. As will be hereinafter more particularly described, upon a rocking movement of the inner arm 194 and an upward movement of the lever 189 to their respective positions indicated in dot and dash lines, the weight of the inner arm 194 causes said pin to ride with the lever 189 at the top of the slot 190 and the pawl 199 to be set back a tooth on the ratchet 200.

Referring particularly to Fig. 1, another rocking shaft 201 is mounted at one end in the standard 197 and at the other in a standard 202. A block 203, adjustably secured to said shaft 201, fixedly carries a bent rod 204 to the outer end of which a finger 205 is adjustably secured. The finger 205 rests on the upper surface of the supply-sheet stack 10 and gradually drops, exerting a torque on the shaft 201, as the height of the stack is diminished by successive sheet deliveries to the conveyer 6. The block and finger adjustments permit the finger to be cooperatively positioned on the stack 10 in accordance with the size of the sheets it contains. The turning movement of the shaft 201 causes a corresponding rocking movement of an arm 206 fixed thereto and slidingly cooperating with a pin carried by an arm 207 fixed to the shaft 196. The upper

most position of the arm 207 is limited by a pin 208 fixed to the standard 197.

A worm 209, fixedly mounted on the shaft 193, meshes with a worm-wheel 210 secured on a shaft 211 rotatably mounted at its ends in bearings carried by the frame plate 188 and by another frame plate (not shown), respectively. The shaft 211 also fixedly carries a sprocket-wheel 212 cooperating with a sprocket-chain 400, one end of which is connected to the magazine 11 and the other end to a balancing weight 401. The magazines 11 and 12 are rigidly carried by vertical rod-supports 402 and 403, respectively. These supports are mounted in and guided for vertical movement by bearing-members 404, but are prevented from rotation, as by keying them therein. The bearings 404 extend from either of the parallel frame plates, one of which only, namely, 188, is illustrated in Fig. 1. The rods 402 and 403 operate through the base 2 and are loosely connected at their lower extremities to a motion-transmitting link 405 pivotally carried by a bracket 406 fixed to said base.

With the members 132 and 134 in mesh, the wheel 182 rotates one complete revolution each time the pedal 80 is depressed by the operator so that the position of the roller 184 in the groove 183 is the same at the start and at the end of each such rotation. Now the groove 183 is so designed that, during such rotation, the lever 185 is carried only once in one direction, causing the rod 189 to be displaced upwardly, and immediately thereafter only once in the opposite direction, causing the rod 189 to be displaced downwardly. This single cycle of motion of the lever 185 occurs at a predetermined time during the operation of the apparatus, as will be hereinafter more particularly described. When the weighted member 192 is in its position shown in full lines in Fig. 24, i. e., in locking engagement with the latch 195, these displacements of the rod 189 have no effect on said member, because of the slot and pin connection of these parts, the pin merely riding first to the top, then to the bottom of the slot 190. However, after a certain number of actuations of the pedal 80, causing removal of a corresponding number of sheets from the supply stack 10, the lowering of the finger 205 will have caused the latch 195 to have swung out of locking engagement with the member 192 through the intermediary of the rocking elements 204, 201, 206, 207 and 196, permitting said member to swing under the influence of its weight until limited in such movement by its pin striking the upper end of the slot 190. Thus, the following operation of the pedal 80 causes the member 192 to swing further in the same direction during the upward movement of the rod 189, the total angular displacement of said member causing the pawl 199 to be positioned on another tooth of the ratchet 200. The downward movement of the rod 189 then carries the member 192 to its normal position, and in this return movement of said member the shaft 193 is predeterminedly rotated by the action of the pawl 199 on the ratchet 200. The shaft 211 is correspondingly rotated through the intermediary of the worm 209 and worm-wheel 210. The corresponding rotation of the sprocket-wheel 212 raises the magazine 211, through the intermediary of the chain 400, bringing the upper surface of the stack 10 to its former level. The finger 205 is thus brought back to its former position, and in this return movement the arm 206 is caused to swing back to its lowermost position, permitting

the arm 207 to follow suit by action of gravity and the latch to be correspondingly restored beneath the weighted arm 194. Obviously, each time the supply magazine 11 is raised in this manner, the storage magazine 12 is lowered correspondingly the same distance. The above-described mechanism for moving the magazines 11 and 12 permits the use of work sheets of varying thickness.

A hand-wheel 419 (Fig. 1) is provided at the rear end of the shaft 193 for adjusting the respective positions of the magazines 11 and 12. Before operating this wheel to lower the magazine 11 and elevate the magazine 12, the pawl 199 must be swung out of engagement with its ratchet 200. Obviously, the starting positions of the magazines 11 and 12 are adjusted in accordance with the height of the stack of work sheets with which the magazine 11 has been supplied.

Assuming the operator to have completed his or her work of addressing a sheet on the platen roll 4, upon actuating the usual typewriter carriage releasing mechanism (not shown), the wheel 149, the lever 151 and the parts carried by said lever are moved by the typewriter carriage to their extreme left positions on the shaft 67, because of their being guided thereon by the brackets 155. Upon depressing the pedal 80, no movement is imparted to the levers 139 and 151 by their respective cooperating grooves 138 and 150 for a certain period of time, during which the roller 162 cooperates with the platen roll 4 in causing ejection of the addressed sheet and the platen roll 4 is sufficiently rotated to permit the addressed sheet, regardless of its size, to travel past the fingers 169. At the end of that period, the first movement of the lever 139 occurs, which causes a new sheet 10 to be transferred to the conveyor 6 to be discharged thereby on the guide plate 5; and the first movement of the lever 151 occurs, thus spacing the roller 162 so as to permit partial passage of the new sheet past the roller 162 in its descent down the guide-plate 5, and advancing the fingers 169 on the platen roll 4 so as to block further ingress of the new sheet. The second movement of the lever 139 occurs immediately after its first, as has been seen, which restores the shoes 16a to their normal positions over the stack 10. Thereafter, the movements of the lever 185 take place in quick succession, which may or may not cause repositioning of the magazines 11 and 12, as has been explained. On the other hand, the groove 150 is so constructed that its cooperating lever 151 is maintained inactive upon completion of its first movement for a slight period of time, during which the new sheet travels through the conveyor 6 and on the plate 5 to be stopped by the fingers 169. At the end of this period of inactivity, the lever 151 undergoes its second movement, which quickly removes the fingers 169 out of engagement with the platen roll, permitting further travel of the new sheet, and simultaneously quickly moves the roller 162 to a position on the platen roll 4 with the inner edge portion of the new sheet therebetween. In other words, the fingers 169 are caused to clear the inner edge of the new sheet substantially at the instant the roller 162 comes into contact with the paper. At the same instant, the platen roll 4, which has been continuously rotated and has either partially or wholly ejected the addressed sheet, causes the new sheet, in conjunction with the roller 162, to travel inwardly on its surface. The new sheet finally comes to rest, properly positioned on the platen roll 4, when the latter stops

rotating, such interruption of rotation occurring, as has already been explained, when the clutching member 105 is forced to become separated from its cooperating member 107 by the action of the pin 110 on the adjustable cam 122. Obviously any one of various size sheets may be accurately positioned, in the manner described, on the platen roll 4, by properly adjusting the position of the handle 115, which controls the extent of rotation 5 of the platen roll 4. The grooves 138, 150 and 183 are evidently so constructed that the levers 139, 151 and 185 are caused to remain inactive upon completion of their respective second movements, the wheels 137, 149 and 182 coming to rest with 10 the rollers 141, 154 and 184 normally positioned relatively to their respective grooves, such interruption of rotation occurring when the members 71 and 74 are declutched by the action of the cam 77 on the cam 79.

20 It now becomes apparent from previous description that, with the typewriter carriage in its extreme left position, the same control, namely the pedal 80, operates to automatically transfer the top sheet of the stack 10 from the magazine 11 into the typewriter 1, without manual rotation of the platen roll 4 being required for locating it in its proper typing position thereon, and to simultaneously automatically remove the already positioned and addressed sheet and convey 25 it for storage in the magazine 12 in its order of succession with relation to the sheets already stored therein. With the new sheet in place on the platen roll, the operator moves the carriage in the usual manner to the right to the position 30 required to start typing on such sheet. During this typing period, the roller 162 cooperates with the platen roll 4 and travels with the typewriter carriage, as in the usual typewriter construction. Should the member 131 on the platen shaft come 35 in contact with the member 129 at the end of a line, the usual typewriter carriage line-spacing lever 178 (Fig. 1) may nevertheless be operated to return the carriage to begin a new line, i. e., to again move the carriage to the right and to 40 rotate the platen to advance the sheet thereon to a position for receiving the next line of typing. In this manner, successive sheets of the stack 10 may be, seriatim, carried to writing position in the typewriter, typed upon, removed from the 45 typewriter and stored. By controlling the extent of rotation of the platen roll with the handle 115, the apparatus will properly insert into the typewriter, remove therefrom and store successive sheets of any one of a plurality of stacks 10 50 differing in the size of the sheets they contain.

Inasmuch as the pedal 80 and some of the parts described, including the shaft 66, also control the operation of the projecting apparatus to be hereinafter described, it is therefore necessary, as when it is desired to operate said projecting apparatus, but to insert and remove sheets in and out of the typewriter 1 in the usual way by hand, to disengage the clutching members 132 and 134 to render the shaft 67 and parts actuated thereby inoperative. This is accomplished by the control 171 which, as shown in Fig. 3, is operated from the front of the apparatus. As illustrated in Figs. 4 and 5, it is pivoted to a bracket 172 fixedly extending from the support 100 and, as illustrated in Figs. 4 and 7, its inner end carries a pin 174 adapted to ride in a circular groove 175 in the member 132. The control 171 also carries a pivoted detent 176 adapted to cooperate with either one of two 55 openings 177 and 178 formed in an extension

179 of the bracket 126. When moved to cause said detent to drop into opening 177, it locks the member 132 to the member 134, and when moved to cause said detent to drop into opening 178, it separates the member 132 from the member 134. 5 When so rendered inoperative, the shaft 67 is provided with a means to prevent rotational displacement thereof, which would otherwise cause the cam-grooves 138, 150 and 183 to lose their proper positions relative to the actuating gear 10 72 and thus to produce improper movements of the levers 139, 151 and 185 and parts controlled thereby, when again the apparatus is operated to automatically insert and remove sheets in and out of the typewriter 1. This means comprises 15 the aforesaid wheel 136, which is provided with a notch 180 normally engaged by a spring-catch 181 carried by a bracket fixed to the support 63. Upon automatic rotation of the shaft 67, the spring 181 slides out of the notch 180 and drops 20 in again at the end of such rotation.

If transfer of typewritten sheets to the storage magazine 12 is not desired, the pivotal portion 7a of the conveyer 7 may be raised, but the automatic rotation of the platen roll 4 may still be 25 utilized for ejecting such sheets therefrom. Also, by operating the control 171 to declutch the members 132 and 134, blanks may be positioned by hand on the guide-plate 5 and the automatic rotation of the platen roll 4 used for properly 30 positioning them thereon. For such occasions, the control 56 (Fig. 16) may, if desired, be operated to stop the conveyer rollers rotating.

Referring to Fig. 1, a magnifying lens or optical system of lenses 220 transmits a divergent beam 35 of light from a light source or lamp 221, which beam after reflection from a mirror 222 is projected on the rear surface of a translucent screen 224. The latter, as shown in Figs. 1 and 3, is so positioned as to be readily observable by the typist during his or her work at the typewriter 1. The lamp 221 is housed beneath the base 2 within a box 225, which is provided with an apertured end 226 for the passage of rays. A dark-box 227 for housing said beam comprises an axially vertical 40 rear section 227a projecting upwardly through the base 2 and carrying at its lower end the optical projecting means 229 beneath said base and an axially horizontal upper section 227b extending forwardly from said rear section 227a 45 and carrying at its forward end portion the screen 224 between apertured plates or frames 229. This box 227 increases in cross-sectional size from the projecting means 229 to the screen 224 to permit unobstructed passage of the divergent beam, the mirror 222 being interiorly disposed at 45 degree angles with the respective axes of the two sections of said box 227. 55

As best illustrated in Figs. 17 and 18, a light transmitting band or film 230, such as is used 60 for motion picture projection and the picture areas or portions of which have the addresses or desired records photographed thereon, is mounted on the usual reels 231 and 231' for travel from one to the other between the optical device 220 65 and the apertured end 226 of the light-box 225. As shown in Fig. 19, the reel 231 is removably keyed to a spool 232, rotatable on a fixed shaft 234. The latter is carried by a vertical frame plate 235, fixedly mounted beneath the base 2. 70 A nut 236 maintains the reel 231 on its spool 232, and a pair of pins 237 riding in a circular groove 239 maintain the spool 232 on its shaft 234. A rear spring 240, acting through the medium of a loose washer, has the effect of a brake, 75

causing resistance to rotation of the spool 232 and reel 231 carried thereby. Similarly, the reel 231' is removably keyed to a spool 232' and held thereon by a nut 236'. The spool 232' is similarly rotationally mounted on a fixed shaft 234', also extending from the plate 235. In like manner, a spring 240' functions to restrain rotational movement of the spool 232' and reel 231' thereon. The film 230, in its travel from one reel to the other, passes over a pair of sprocket wheels 241 and 241', the cogs of which cooperate with the usual openings 242 disposed along one of the marginal edges of said film. In a manner which will be more clearly understood hereinafter, pulleys 244 and 244' respectively cooperate with the wheels 241 and 241', the pulley 244 being connected with the spool 232 by a slip or friction belt 245 and pulley 244' being connected with the spool 232' by a slip or friction belt 245'.

Referring to Figs. 18 and 20, a shaft 246 is rotatably mounted in rear bearings 247 fixed to the plate 235 and carries a gear 248 rotatable therewith. As will be seen, this shaft 246 is successively actuated at the right moments, to produce successive displacements of the film 230 in one direction or the other behind the lens or lenses 220, its extent of rotation being one complete revolution and its direction of rotation the same on each occasion. Also fixed to the plate 235 at the rear thereof, are a pair of bearings 249, in which a shaft 250 is both rotatably and slidably mounted. The shaft 250 fixedly carries at its ends bevel gears 251 and 251' and also fixedly carries between said bearings 249 a central gear 252 constantly meshing with the gear 248. Said gear 252 is provided with a hub portion formed with a groove 254 in which rides a pin 255 fixed to the rear portion of a control 256 extending through the plate 235. This control 256 is pivoted to a front bracket 257 extending from the plate 235 and is provided with a spring-pressed pin 259 adapted to slidably enter any one of three recesses 260 formed in said bracket 257. When the pin 259 is caused by the handle 256 to engage the opening 260 at the right in Fig. 18, the gear 251 is caused to mesh with a cooperating bevel-gear 261, and when the pin 259 is caused by the handle 256 to engage the opening 260 at the left in said figure, the gear 251' is caused to mesh with a cooperating bevel-gear 261'. When the control is operated to cause the pin 259 to drop into the center recess 260, both gears 251 and 251' are out of mesh with their respective cooperating gears 261 and 261'. The latter gears are respectively fixedly mounted at the rear ends of shafts 262 and 262', extending forwardly through the plate 235. The gears 261 and 261' and fixed collars 264 and 264' prevent the shafts 262 and 262' from becoming axially displaced. Shaft 262 carries the aforesaid wheel 241 and pulley 244 and shaft 262' carries the aforesaid wheel 241' and pulley 244'. The wheels 241 and 241' are fixed to their respective shafts, but the pulleys 244 and 244' are slidably mounted thereon to permit them to be moved into and out of mesh with their respective cooperating members 241 and 241' under the influence of controls 265 and 265'. As shown in Fig. 20, the control 265 is pivoted to a fixed bracket 266 extending forwardly from the plate 235 and carries a pin riding in a circular groove 269 in the pulley member 244. A rearward extension 270 is provided with a spring-pressed pin 271 adapted to slidably enter either one of two recesses 272 formed in the bracket 266. In con-

struction and operation, the control 265' is identical to the control 265 described.

Observing the direction of rotation of the actuating shaft 246 (that of the arrow in Fig. 20), it now becomes apparent that, with the control 256 thrown to the extreme right in Fig. 18 and the controls 265 and 265' respectively positioned to lock the pulley 244 to the sprocket wheel 241 and to unlock the pulley 244' from the sprocket wheel 241', a rotation of said shaft 246 will cause a corresponding rotation of both the sprocket wheel 241 and pulley 244 in such a direction as to unwind the film 230 from the reel 231' and wind it on the reel 231, the sprocket wheel 241 causing a displacement of the film 230 exactly in proportion to the extent of rotation of the shaft 246 and the slip belt 245 permitting the amount of film displaced to be wound on the reel 231. In the meanwhile, the sprocket wheel 241' is rotated idly by the film 230 and the pulley 244' is rotated idly by the belt 245'. By throwing the control 256 to the extreme left in Fig. 18 and reversing the positions of the handles 265 and 265', the same rotation of the actuating shaft 246 will now cause the sprocket wheel 241', the pulley 244' and the slip belt 245' to move the film 230 the same amount in the opposite direction and wind this amount on the reel 231'. The gears 248 and 252 are so designed that, for each rotation of the shaft 246, the film 230 is caused to advance, in one direction or the other depending on the positions of the controls 256, 265 and 265', the distance of one of its picture areas, so that, as will be hereinafter more clearly understood, the picture areas of the film may be successively brought into proper position before the projecting means 220. With the control 256 in its neutral or center position, the projecting apparatus is no longer automatically operated, no displacement of the film taking place by actuation of the shaft 246. Moreover, the film 230 can then be displaced by a crank 274 positioned on either one or the other of the sprocket wheel ends 275 and 275', depending on the positions of the controls 265 and 265' or the direction of travel desired, so that, whenever desired, any particular picture portion may be brought into position before the lens or lenses. Idlers or friction wheels 276 and 276' bear down on the sprocket wheels 241 and 241' for maintaining the film thereon and may be pivoted out of the way by respective handles 277 and 277'.

Referring to Fig. 16, the support 29 is formed with another bearing portion 279 in which the motor shaft is rotatably carried. Said motor shaft also extends through another support 280 and loosely carries between said supports a worm 281, which meshes with a worm-wheel 282 loosely mounted on the aforesaid shaft 246. The worm 281 is formed at one side with a toothed portion 284 to cooperate with a spring-pressed clutching member 286 slidably keyed to the motor shaft. Axial displacement of the worm 281 is prevented by an inner collar 285 fixed to the motor shaft. A control 289 pivoted to a bracket 290 extending from the support 29 operates on the member 286 to either separate it from or mesh it with its cooperating member 284. The control 289 is provided with a spring-pressed detent 291 to engage an opening in the bracket 289 for maintaining the member 286 in its declutched position. The control 289 is moved to its clutching position causing the members 284 and 286 to mesh, when it is desired to displace the film 230 by actuation of the shaft 246.

Referring to Fig. 1, the shaft 246 is rotatably

carried by other supports 292 fixed to the base 2. Axial displacement of this shaft is prevented by fixed collars 294. The wheel 282 is provided at one side with a clutching portion 295 to cooperate with a clutching member 296 slidably keyed to the shaft 246. Axial displacement of this wheel is prevented by an inner fixed collar 297. Movement of the member 296 to force it in meshing engagement with the member 295 is provided by a spring 299, properly positioned on the shaft 246 by a fixed collar 300, but the member 296 is normally restrained from such movement by a bar 301, on the cam end of which normally bears a pin 302 outwardly extending from the member 296. The bar 301 is slidably mounted in a support 304 fixed to the base 2 and is provided with a notch normally engaged by a latch 305 slidably guided on the support 304. The latch 305 is actuated, as will be seen, at a predetermined moment to release the bar 301, which then moves with the pin 302 and member 296 under the influence of the spring 299. Upon rotation of the shaft 246, the pin 302 rides off the bar 301, which is then restored to its normal position by a spring 306 acting on a pin 307 fixed to the bar 301. The spring 306 is attached at one end to the support 304 and the pin 307 projects through a slot 309 formed in said support 304.

Referring to Figs. 4 and 7, the shaft 66 carries at its outer end a gear 311 removably secured to said shaft, as by a key 312 and nut 314. The gear 311 meshes with a gear 315 removably mounted on a fixed shaft 316 (Fig. 9), extending from the side plate 8. A bell-crank 317 is pivotally carried by the side plate 8 and has an arm 317a normally positioned in the path of movement of a pin 319 extending laterally from the gear 315, which is rotatable in the direction of the arrow in Fig. 9. To the other arm 317b of said bell-crank is pivotally attached the upper end of a vertical rod 320, which, as illustrated in Figs. 1 and 16, extends through the base 2 and is pivotally attached at its lower end to one end of a link 321 pivotally carried beneath the base 2. The link 321 at its other end is pivotally attached to another link 322, which is pivotally connected to and serves to actuate the latch 305. A spring 324, acting on a collar 325 fixed to the rod 320, maintains the latch 305 in its normal lowermost position engaging the aforesaid notch in the bar 301, the rod 320 then being in its normal uppermost position.

Each time the arm 317a is actuated by the pin 319, the downward movement of the rod 320, against the force of the spring 324, causes the latch 305 to unlock the bar 301, this, as has been seen, permitting the shaft 246 to rotate, the control 289 being assumed in clutching position. Upon the pin 302 riding off the bar 301 and the pin 319 riding off the arm 317a, the latch 305 is restored to its normal position in locking engagement with the bar 301, by reason of the action of the springs 306 and 324. The shaft 246 rotates exactly one revolution, further rotation being prevented because of the cam action of the bar 301 on the pin 302, which causes the latter to declutch the member 296 from its cooperating member 295, as well as resume its normal position on the bar. This full revolution of the shaft 246, as has been seen, displaces the film 230 and brings another of its picture areas into position before the projecting means 220.

Obviously, the gears 311 and 315 are caused to be rotated each time the pedal 80 is depressed by

the operator. However, in view of the fact that the film 230 may bear a given number of addresses or records in each of its picture portions, it may not be desirable to have the pedal 80 cause actuation of the shaft 246 each time or on every occasion it is depressed, but only after all the projected records of one picture area have been copied on the typewriter. Now, observing that the gears 311 and 315 go through the same extent of rotation each time the pedal is depressed, it necessarily follows that they may be so chosen as to cause a definite relation between the number of times the pedal is depressed and the number of times the shaft 246 is actuated. Thus, the number of records in a picture area of the film dictates the ratio of pitch line diameters or of number of teeth the gears 311 and 315 should bear. In the embodiment of the invention illustrated, the gear 315 carries six times as many teeth as the gear 311. Observing that the gear 311 rotates with the shaft 66 one complete revolution each time the pedal 80 is depressed, consequently the shaft 246 is rotated and the film 230 displaced the distance of one of its picture areas once for every sixth time the pedal 80 is depressed. This arrangement of gears 311 and 315 evidently provides for six records in each picture portion of the film. Should the succeeding film or a particular sequence of the same film differ in the number of records per band portion, the gears 311 and 315 are replaced by a new set bearing the proper ratio to one another, the replacing gear 315 being also provided with a pin 319. For example, if it is desired to have the film advanced to cause a different picture area to be positioned for projection each time the pedal is operated, the new gears 311 and 315 should be identical to one another.

Preferably, the idle position or positions of the pin 319 are such that it bears against or is close to the crank arm 317a prior to the rotation of the gear 315 causing displacement of the film, so that said pin may rock said arm at the start or soon after the start of such rotation. Obviously, the radial position of the pin 319 and the construction of the arm 317a are such as to permit the use of different size gears 315.

As best illustrated in Figs. 13 and 14, a shutter or band 326 of suitable sheet material, such as the trade product known as "celluloid", is mounted for travel behind the screen 224 between two rollers 327 and 329 rotatably mounted in the side walls of the casing portion 227b and to which opposite end edges of said band are respectively secured. The lower part 326a of this band is opaque, except at a central portion 330, which is transparent and of such dimensions as to permit projection, on the screen 224, of only one of the addresses or records contained in a picture area of the film 230 (see Fig. 3). The upper part 326b, shown wound on the upper roller 329 in Figs. 13 and 14, is transparent and, as will be seen, may be caused to be positioned behind the screen 224 to permit projection thereon of the entire extent of each picture area. The upper roller 329 is equipped with a spring 331, which serves to wind the shutter on the surface of said upper roller, as well as to keep it taut between the two rollers. A pin 332 fixed to the lower roller 327 cooperates with an adjustable stop or crank-arm 334 to arrest or limit the winding action of the spring 331. This stop 334 is formed at the inner end of a rod 335 threaded through the front of the projector box and carrying a hand-wheel 336 at its outer end. A lock- 75

nut 337 secures the rod in its adjusted position. The lower roller 327 is provided at one side with a ratchet wheel 339 fixed to its shaft. Normally engaging said ratchet 339 are a pair of dogs, 340 and 341, the respective purposes of which are to intermittently displace the two rollers and shutter and to maintain those parts in their displaced positions, against the force of the spring 331. As will be more clearly understood, at a predetermined moment these dogs are caused to disengage the ratchet 339, the rollers and shutter then returning under the influence of the spring 331 to their original positions, as determined by the adjustable stop 334. Thus, the first or uppermost position of the transparent shutter portion 330 back of the screen 224 is adjustable by the hand-wheel 336.

Referring to Figs. 4 and 5, the aforesaid member 101 carries a crank-stud 345 on which is pivotally mounted the lower end of a link 346. Referring particularly to Figs. 3 and 15, the link 346 at its upper end is pivotally attached to a crank or rocking arm 347 fixed to a horizontal shaft 349 carried by the side plates 8 and 8a at their upper edges. This shaft 349 has also fixed thereto a similar arm 350 to which is pivotally attached the lower end of a link 351 (see Figs. 1 and 2). As best illustrated in Figs. 13 and 14, this link 351 extends through an aperture in the projector box and is pivotally carried at its upper end by a bolt 352 adjustably secured, as by a nut 353, in the slot 354 formed in a lever or crank 355 loosely carried by the shaft of the lower roller 327. Access to the nut 353 for its adjustment is had through a side door 357 (Fig. 2) of the projector box 227. The crank 355 carries at its end the dog 340, a spring 356 attached to that dog 340 and to the crank 355 causing the dog 340 to normally engage the ratchet wheel 339.

As illustrated in Figs. 1 and 9, a link 358 is pivotally attached at its lower end to the arm 317b of the bell-crank 317. Referring to Figs. 1 and 15, this link 358 at its upper end is pivotally attached to a crank or rocking arm 359 fixed to a second horizontal shaft 360 carried by the side plates 8 and 8a at their upper edges. A similar arm 361 is fixed to the shaft 360 and to this arm 361 is pivotally attached the lower end of a rod 342. As shown in Figs. 13 and 14, the rod 342 at its upper end portion extends through an aperture in the projector box through the outer arm 362a of a pivoted link 362, the inner end of which is adapted to slidably cooperate with the outer arm 340a of the dog 340. The rod 342 further extends through the outer arm 341a of the dog 341, which is pivotally carried by a fixed bracket 364. A spring 365, attached to the arm 341a and to a fixed bracket 366, causes the dog 341 to normally engage the ratchet wheel 339. Fixed collars 367 and 369 are carried by the rod 342 and are so positioned that, upon their downward movement with the rod, they act against the force of the springs 356 and 365 to rock the arms 362a and 341a and thereby cause the dogs 340 and 341 to move out of engagement with the ratchet 339, respectively. Upon release of the rod 342, the springs 356 and 365 restore the dogs to their normal positions on the ratches 339.

The rod 358 is actuated only when the apparatus operates to displace the film 230 as a result of the pin 319 striking the bell-crank arm 317a, and on each of these occasions is caused to quickly move downwardly and acts, through the intermediary of the crank 359, shaft 360,

crank 361 and rod 342, to release the ratchet 339 from the dogs 340 and 341, said rod 358 and parts movable therewith being obviously restored by spring action to their normal positions when the pin 319 leaves the surface of the arm 317a. On the other hand, observing that reciprocating motion is imparted to the rod member 346 by a rotation of the crank member 101 and that the latter rotates one complete revolution during each operation of the apparatus (the gears 72 and 97 bearing a one to one ratio to one another), said rod 346 acts, through the intermediary of the crank 347, shaft 349, crank 350 and rod 351, to move the slotted lever 355 once in one direction and thereafter once in the opposite direction to its starting position, each time the pedal 89 is depressed by the operator. Now, during each operation of the apparatus which does not effect release of the ratchet 339, the first movement of the lever 355 causes the dog 340 to rotate the ratchet 339 and roller 337 to lower the position of the transparent shutter portion 330 back of the screen, and the second movement of the lever 355 brings the dog 340 back into initial position on the ratchet 339, held in its displaced position by the dog 341. The extent to which the shutter portion 330 is displaced by movement of the lever 355 is determined by the position of the connecting pin or stud 352 in the slot 354, and this position is so adjusted as to accord with the number of addresses or records per picture area of the film 230, i. e., as to permit projection of a different record through the shutter portion 330 in each of its successively lowered positions. Thus, in turn each of the records of the picture portion, positioned in co-operative relation with the projecting lens system 220, is projected and brought into view of the screen 224. When the shutter portion 330 has reached its lowermost position, i. e., when the last record of said picture portion has in this manner been exposed to view, the next operation of the apparatus functions not only to properly displace the film 230 to bring the succeeding picture area into position before said device 220, as has been seen, but also to release the ratchet 339 by automatic actuation of the rod 342, whereby the shutter portion 330 is raised by spring action to its original position, as determined by the stop 334, and exposes to view the first record of said succeeding area. It is to be particularly noted that, therefore, the same control, namely the pedal 89, which operates to remove a type-written sheet from and to insert a new one into the typewrite 1, also operates to move both film and shutter at the right moments to bring on each occasion a new record into view, whereby no error in the copying of records is possible.

Obviously, the pin 319 and the film 230 are so positioned at the start that, upon depressing the pedal, the first picture area is positioned before the lens system 220 and the shutter portion brought, by automatic release of the ratchet 339, to its uppermost position.

As best shown in Fig. 13, the rod 342 is provided at its lower end with an elongated slot 378 through which extends the pin or element connecting the rod to the crank 361. Such connection normally rests at the bottom of said slot 378, whereby manual movement of the rod to remove the dogs 340 and 341 from their ratchet 339 is permitted. When automatic actuation of the shutter is not desired, the rod 342 may be maintained in its ratchet releasing position by a control, comprising a hand-wheel 371 rotatably

carried by the bottom of the casing portion 227b and a projection 371a cooperating with a pin 342a fixed to the rod 342. The lower roller 327 is provided at its other side with another ratchet-wheel 372 fixed thereto or to its shaft and with a hand-wheel 374 by means of which it may be rotated. A dog 375 may be pivoted into and out of engagement with the latter ratchet 372 by means of a hand-wheel 376. Thus, with the stop 334 pivoted out of the path of the pin 332, the shutter may be wound on the roller 327, as when it is desired to position its transparent portion 326b back of the screen 224, for example when each of the picture areas of the film contains but a single record. When automatic operation of the shutter is again desired, the dog 375 is swung out of engagement with its ratchet 372, the control 371 is operated to restore the dogs 340 and 341 on their ratchet 339, and the wheels 336 and 374 rotated to return the stop 334 and the pin 332 to their operative positions. The wheel 374 may be used to lower the position of the transparent shutter portion 330, whenever desired. If required, said portion 330 may be positioned whenever desired back of the screen and its automatic operation prevented. Manual operation of the rod 342 facilitates adjusting the relative positions of the rod 351 and slotted lever 355.

It now becomes apparent that I have provided an apparatus satisfying the various objects of the invention.

What is claimed is:

1. The combination with a typewriter having a platen roll and means for guiding a sheet to said platen roll, of an apparatus for automatically placing said sheet in writing position on said platen roll comprising control means, a roller to cooperate with said platen roll in starting displacement of said sheet on said platen roll, a sheet stop adjacent said platen roll and normally out of sheet-arresting position, means rendered operative by said control means for moving said roller relatively to said platen roll to permit said sheet in its travel on said guiding means to partially pass said roller and for moving said sheet stop into sheet-arresting position to block further ingress of said sheet, means rendered operative by said control means for moving said sheet stop out of sheet-arresting position and for moving said roller into cooperative relation to said platen roll and into impinging relation to said sheet, and means for adjusting the extent of rotation of said platen roll.

2. The combination with a typewriter having a platen roll, of a sheet-supply station, a sheet-storage station, a control, means rendered operative by said control for rotating said platen roll, means operating in response to each actuation of said control for transferring one sheet from said sheet-supply station to said platen roll, means for gripping a sheet positioned on said platen roll as it is ejected by such rotation of said platen roll and conveying it to said sheet-storage station, a roller to cooperate with said platen roll in starting displacement on said platen roll of a sheet transferred to said platen roll and normally cooperating with said platen roll, a sheet stop ahead of said roller and normally out of sheet-arresting position, means rendered operative by said control and operating only after travel of an ejected sheet past said roller and said sheet stop for moving said

roller relatively to said platen roll to permit a sheet transferred to said platen roll to partially travel past said roller and for moving said sheet stop into sheet-arresting position to block further ingress of a sheet transferred to said platen roll, means rendered operative by said control for restoring said roller and said sheet stop to their respective normal positions with said roller engaging a sheet transferred to said platen roll, and means for insuring the stacking of the sheets at said sheet-storage station in a superimposed relation according to their order of ejection from said platen roll.

3. The combination with a typewriter having a platen roll and means for guiding a sheet to said platen roll, of an apparatus for automatically placing said sheet in writing position on said platen roll and comprising control means, means rendered operative by said control means for rotating said platen roll, a sheet stop adjacent said platen roll and normally out of sheet-arresting position, means rendered operative by said control means for cooperating for moving said sheet stop into sheet-arresting position to arrest said sheet in its travel on said guiding means and for thereafter moving said sheet stop out of sheet-arresting position, and means to cooperate with said platen roll in displacing said sheet thereon from its arrested position.

4. The combination with a typewriter having a platen roll and means for guiding a sheet to said platen roll, of an apparatus for automatically placing said sheet in writing position on said platen roll and comprising control means, a roller to cooperate with said platen roll for starting displacement of said sheet on said platen roll, a sheet stop adjacent said platen roll and normally out of sheet-arresting position, means rendered operative by said control means for moving said roller relatively to said platen roll to permit said sheet in its travel on said guiding means to partially pass said roller and for moving said sheet stop into sheet-arresting position to arrest said sheet against further ingress, means rendered operative by said control means for moving said sheet stop out of sheet-arresting position and for moving said roller into cooperative relation to said platen roll and into impinging relation to said sheet, and means rendered operative by said control means for rotating said platen roll.

5. The combination with a typewriter having a platen roll, of a sheet-supply station, a control, means rendered operative by said control for transferring one sheet from said station to said platen roll each time said control is actuated, means rendered operative by said control for rotating said platen roll, a sheet stop adjacent said platen roll and normally out of sheet-arresting position, means rendered operative by said control for moving said sheet stop into sheet-arresting position to arrest the transferred sheet and for thereafter moving said sheet stop out of sheet-arresting position, and means rendered operative by said control for cooperating with said platen roll in displacing the transferred sheet thereon from its arrested position.

6. The combination with a typewriter having a platen roll, of a sheet-supply station, a control, means operating in response to each actuation of said control for transferring one sheet from said station to said platen roll, a roller adapted to cooperate with said platen roll in starting displacement of each transferred sheet on said platen roll and normally cooperating with said platen roll, a sheet stop ahead of said roller in

the direction of travel of the transferred sheet: and normally out of sheet-arresting position, means rendered operative by said control for moving said roller relatively to said platen roll to permit the transferred sheet to partially pass said roller and for moving said sheet stop into sheet arresting position to stop movement of the transferred sheet, and means rendered operative by said control for restoring said roller and said stop to their respective normal positions with said roller engaging the transferred sheet on said platen roll.

7. The combination with a typewriter having a platen roll, of a sheet-supply station, a control, means operating in response to each actuation of said control for transferring one sheet from said station to said platen roll, a roller adapted to cooperate with said platen roll in starting displacement of each transferred sheet on said platen roll and normally cooperating with said platen roll, a sheet stop ahead of said roller in the direction of travel of the transferred sheet and normally out of sheet-arresting position, means rendered operative by said control for moving said roller relatively to said platen roll to permit the transferred sheet to partially pass said roller and for moving said sheet stop into sheet-arresting position to stop movement of the transferred sheet, means rendered operative by said control for restoring said roller and said stop to their respective normal positions with said roller engaging the transferred sheet on said platen roll, and means rendered operative by said control for rotating said platen roll.

8. The combination with a typewriter having a platen roll, of a sheet-supply station, a control, means operating in response to each actuation of said control for transferring one sheet from said station to said platen roll, a roller adapted to cooperate with said platen roll in starting displacement of each transferred sheet on said platen roll and normally cooperating with said platen roll, a sheet stop ahead of said roller in the direction of travel of the transferred sheet and normally out of sheet-arresting position, means rendered operative by said control for moving said roller relatively to said platen roll to permit the transferred sheet to partially pass said roller and for moving said sheet stop into sheet-arresting position to stop movement of the transferred sheet, means rendered operative by

said control for restoring said roller and said stop to their respective normal positions with said roller engaging the transferred sheet on said platen roll, means rendered operative by said control for rotating said platen roll, and means for adjusting the extent of rotation of said platen roll.

9. The combination with a typewriter having a platen roll, of a sheet-supply station, a control, means rendered operative by said control for transferring one sheet from said station to said platen roll each time said control is actuated, a feed stop adjacent said platen roll and normally out of sheet-arresting position, means rendered operative by said control for moving said sheet stop into sheet-arresting position to arrest the transferred sheet and for thereafter moving said sheet stop out of sheet-arresting position, and means rendered operative by said control for cooperating with said platen roll in displacing the transferred sheet thereon from its arrested position.

10. In combination with a typewriter having a platen roll, of a sheet-supply station, a sheet-storage station, a control, means rendered operative by said control for rotating said platen roll, means operating in response to each actuation of said control for transferring one sheet from said sheet-supply station to said platen roll, means for gripping a sheet positioned on said platen roll as it is ejected by such rotation of said platen roll and conveying it to said sheet-storage station, a roller to cooperate with said platen roll in starting displacement on said platen roll of a sheet transferred to said platen roll and normally cooperating with said platen roll, a sheet stop ahead of said roller and normally out of sheet-arresting position, means rendered operative by said control and operating only after travel of an ejected sheet past said roller and said sheet stop for moving said roller relatively to said platen roll to permit a sheet transferred to said platen roll to partially travel past said roller and for moving said sheet stop into sheet-arresting position to block further ingress of a sheet transferred to said platen roll, and means rendered operative by said control for restoring said roller and said sheet stop to their respective normal positions with said roller engaging a sheet transferred to said platen roll.

ROBERT STUART.
